Term of patent 14 years

(Cl. D29—23)

FIGURE 1 is a front elevational view of a wall plaque showing my new design;

FIGURE 2 is a side elevational view thereof, partially sectioned along the line 2—2 of FIGURE 1, and

FIGURE 3 is a rear elevational view thereof.

The dominant features of the wall plaque reside in a generally rectangular flame shaped body provided with fingers projecting from substantially the full extent of both the vertical sides and top portion thereof, said projecting fingers of flame having all edge portions sloped inwardly to provide a three-dimensional appearance.

I claim:

The ornamental design for a wall plaque, as shown and described.
